Samuel W. Gibbs of Albany, N. Y. Ass. or to
Fugger, Treadwell & Perry
Letter Patent No. 356 - dated Mar. 4, 1851.

~~~~~
The Schedule referred to in these Letter Patent and making part of the same.

To all to whom these presents shall come:

Be it known, that I, Samuel W. Gibbs, of the City of Albany, and State of New York, have produced a new ornamental design, for the embellishment of a six plate stove; and I declare the annexed and accompanying drawings to be a full and accurate delineation thereof.

Fig. 1 representing the ornamented Top plate.

Fig. 2 representing the ornamented End plate.

Fig. 3 representing the ornamented Side plates.

Fig. 4 representing the ornamented bottom plate.

Fig. 5 representing the front & Fig. 6 the profile of the leg - & Fig. 7 an enlarged view of a section of the damper on the hearth. The ornaments being carried round symmetrically on the plates, where partially represented in the drawings.

What I claim, and desire to secure by Letters

Patent, is the combination and arrangement of ornamental figures & forms, represented in the annexed drawings, as making an ornamental design for a six plate stove.
